Primary Examiner — Clare E Heflin(74) *Attorney, Agent, or Firm* — Beeson Skinner Beverly, LLP(57) **CLAIM**

The ornamental design for a wall mounted lighting fixture, as shown and described.

DESCRIPTION

FIG. 1 is a top front perspective view of a wall mounted lighting fixture showing our new design;

FIG. 2 is a front elevational view thereof;

FIG. 3 is a right side elevational view thereof, the left side being a mirror image;

FIG. 4 is a rear end elevational view thereof;

FIG. 5 is a bottom plan view thereof; and,

FIG. 6 is a top plan view thereof.

The broken lines shown in FIGS. 1 and 3-6 represent a junction box mounted in a wall to which the claimed wall mounted lighting fixture is attached. The junction box forms no part of the claimed design.
